CEMENT WORKING TOOL

Leigh S. Brunson, Milwaukee, Wis.

Application November 4, 1952, Serial No. 22,124

Term of patent 14 years

(Cl. D51—1)

To all whom it may concern:

Be it known that I, Leigh S. Brunson, a citizen of the United States, residing at Milwaukee in the county of Milwaukee, State of Wisconsin, have invented a new, original, and ornamental Design for a Cement Working Tool, of which the following is a specification, reference being had to the accompanying drawing, forming a part thereof, wherein:

Figure 1 is a front elevational view of the cement working tool showing my new design;

Figure 2 is a top plan view of the tool;

Figure 3 is an end view of the tool as seen from the right in Figure 1; and

Figure 4 is an end view of the tool as seen from the left in Figure 1.

I claim:

The ornamental design for a cement working tool, substantially as shown.

LEIGH S. BRUNSON.
